UNITED STATES PATENT OFFICE.

IRVING R. PIERSON, OF NEW YORK, N. Y.

MEANS FOR METAL-STRAPPING AND SEALING CONTAINERS.

1,400,624.

Specification of Letters Patent. Patented Dec. 20, 1921.

Application filed March 30, 1921. Serial No. 457,130.

To all whom it may concern:

Be it known that I, IRVING R. PIERSON, a citizen of the United States, residing at New York city, in the county of New York and State of New York, have invented certain new and useful Improvements in Means for Metal Strapping, and Sealing Containers, of which the following is a specification, reference being had to the accompanying drawings.

It is the purpose of the present invention to provide a device wherein means is afforded for preventing theft or pilferage without detection, in opening containers during transportation.

Another purpose is to provide double metal strappings, one overlying the other, the latter being connected to the container, with means connecting the double strappings in combination with means for connecting and sealing the ends of the latter strapping, so that neither one of the strappings can be detached from the container, without detection.

Still another purpose is the provision of a device wherein coupled overlying straps are passed about a container, the under one being secured to the container, preferably to each board thereon, in case the container is made of wood, with a sealing cup and seal, so connecting the ends with the overlying strap, as to prevent the removal of the under strap or the separation of the two straps, without destroying the seal, and which will readily disclose the fact that the strapping of the container has been tampered with.

While the design and construction at present illustrated and set forth is deemed preferable, it is obvious that as a result of a reduction of the invention to a more practical form for commercial purposes, the invention may be susceptible of changes, and the right to these changes is claimed, provided they are comprehended within the scope of what is claimed.

The invention comprises further features and combination of parts, as will be herein after set forth, shown in the drawings and claimed.

In the drawings:—

Figure 1 is a view in perspective showing one end of a container, preferably constructed of wood, showing the coupled metal straps surrounding the same, and showing

the ends of the outer strap connected and sealed.

Fig. 2 is an enlarged detail sectional view on line 2—2 of Fig. 1, through the preferred embodiment of the invention, showing the connection and sealing of the adjacent ends of the outermost strap.

Fig. 3 is a cross sectional view on line 3—3 of Fig. 2.

Fig. 4 is an enlarged detail sectional view through a modified construction, wherein the outermost strap has prongs engaging pockets of the under strap, which is fastened to the walls of the container by nails or tacks or other fasteners.

Fig. 5 discloses perspective and bottom plan views of the sealing die for fastening the seal 14.

Fig. 6 is a view in elevation of a portion of a metallic strap 5.

Referring to the drawings, 1 designates a container, which may be constructed of any suitable material, preferably boards of wood, and engaged about either or both ends of the container is a metallic strap 2, which may be any suitable length, width and thickness. This strap is provided at intervals with transversely disposed slots 3, the metal 4 between the slots being struck up, thereby providing loops through which a second metallic strap 5 passes. The metallic strap 2 is fastened to the walls of the container, preferably each and every board, by means of tacks, nails or other fastenings 6 alternately with the loops. The metallic strap 2 is designed to be of sufficient length to pass about any size container, it being obvious that the strap may be cut off from a reel or spool of strap, sufficient to fit any size container.

The strap 5, which is passed through the loops of the strap 2 has its ends overlapped, as shown, and pass through an opening 7, formed longitudinally through the body of a seal cup 8, which may be any suitable construction preferably as shown. A king nail 10 or tack 9 is driven through openings 10 in the upper and lower walls of the passage through the base or body of the seal cap, and through the sheet metal straps, and into the container. In this way the adjacent overlapping ends of the outermost strap are connected.

The seal cup has upon its margin an upstanding wall 11. In fact the seal cap has a depression 12 caused to be formed by the up-

standing wall 11. The inner longitudinal and arcuate walls of the depression 12 are beveled or under-cut as shown at 13, to be engaged by the seal 14. This seal is preferably constructed of any suitable soft metal, and is slightly arcuate in shape, transversely and longitudinally, so that the seal is capable of passing through the reduced portions of the depression, for the purpose of covering the king nail, pin or tack or other fastening 9. This seal 14 is likewise slightly beveled on its edge, and when it is inserted in the depression, it is flattened out, so that its beveled side and end walls may conform to and engage the under-cut walls of the depression. This seal 14 may be flattened out by means of a suitable sealing tool, such as indicated in Fig. 5 and designated by the numeral 15. This sealing tool is of a shape or contour substantially conforming to and approximately the size of the seal 14, so that when the seal is flattened out, the soft metal of the seal will be forced into engagement with the under-cut walls of the depression very tightly, and in such wise, as to prevent removal of the seal without detection, in other words without mutilating or destroying the seal, that it would be impossible to replace it, without showing that it has been tampered with. The sealing tool may be provided with a die face, with any suitable printed matter thereon, such as shown in the drawings as indicated at 16, so that when the seal is flattened or pressed into place, the impression of the die will be imparted to the face of the seal.

With a device of this kind it is possible to bind containers, preferably those made of wood, and seal the binding, in order to prevent the removal of the same without detection.

In Fig. 4 the loops are eliminated, and in their stead the metallic strap 2 has transverse openings 17, the metal 18 adjacent thereto being struck up, to form pockets 19, for the reception of tongues or tangs or projections 20, which are struck up from the metallic strap 5. These prongs or tangs when cut from the metallic strap leave openings 20^a as shown. By this method the metallic straps may be the same width, where as in the Figs. 1 to 3 inclusive, the metallic strap 5 is of less width than the metallic strap 2, by reason of the fact that the strap 5 passes through the loops. However in this modified embodiment of the device, the sealing and connecting of the adjacent ends of the outermost strap is the same, as in Figs. 1 to 3 inclusive.

The strap 5 like the strap 2 may be cut from a reel or spool of sheet metal shape, which is relatively thin, it depending upon the size of container to be bound. In Figs. 3 and 4 the seal 14 is shown in dotted lines, ready to be inserted into the depression and

flattened. In this manner it is shown that the seal is of arcuate form transversely and longitudinally, so as to permit of the insertion of the seal through the reduced part of the depression.

In striking up the prongs 20 on the strap 5 in the modified construction in Fig. 4, the openings 20^a caused to be formed by striking up the tongues, act to receive the struck up metal adjacent the walls 19. Receiving of the struck up metal into the openings 20^a is due to the fact that the openings 20, though they are struck up from the metal of the strap 5, are not bent back, but are simply reflected, and assume positions somewhat adjacent the openings 20^a, so as to insure the proper fit of the straps, when one overlies the other.

While the drawing illustrates the coupled overlapped straps passing about the container crosswise, in fact around the sides, it is obvious that the coupled overlapping straps may pass about containers in any direction, either cross wise, lengthwise, and over the ends, or in any manner, as may be found necessary, in order to cover boards, which may be forced out of place, in case the metal strappings are not used.

In Fig. 1, it is shown that the double or overlapping coupled straps may be used around the heads of the container, at least one nail passing through the under strap 2, into each board of the container, into each board of the head, and if necessary additional nails may be used. These overlapping straps in Fig. 1 are shown as passing over one head of the container, near one side, and it is obvious that others may be used on the head adjacent the other side of the container. Also the straps may extend at right angles to the straps extending over the corner. The

nails used in fastening the under strap 2 are driven home, at locations immediately under the strap 5. Also the inner ends of the nails, may be clenched on the inner surface of the container, before the container is filled with goods, and such straps which may pass about the heads of the container are nailed down in this manner, and to the side boards of the container, as well as the heads, and as previously stated the nails are driven so that the heads of the nails will assume positions under the protecting straps 2 and 5, which pass about the container crosswise. In other words the system of strapping is such that each container, before it is filled with goods, and before the top is placed thereon, is supplied with double overlapping coupled straps, extending horizontally about the heads and sides of the container, one near the top of the container, and one near the bottom. The under strap 2 is first applied, there being nails driven through the strap and into each board of the container, and their inner ends clenched, before the con-

tainer is filled with goods or merchandise. The top of the container is then placed, and nailed securely, after which the double overlapping coupled straps are passed about the 5 container transversely or crosswise, overlying the horizontal strapping. In fact by these double overlapping coupled straps passing transversely or crosswise, over the top, sides and bottom the horizontal strappings 10 are protected, and where the protecting double strappings intersect the horizontal strappings, nails are driven into the container, so that their heads are covered and protected, in such wise as to prevent access 15 thereto. In this way the shipper is doubly assured, that the container will not be fraudulently tampered with, without disclosing, or showing evidence of the act. Furthermore the principal idea of the invention is 20 the driving of sufficiently long cement nails through the strap 2 and through each board on the sides, top, bottom and heads of the container, the outer strap 5 which passes through the loops on the strap 2 cover the 25 heads of the nails, so that no instrument can be used to extract the nails, cementing the ends of the straps 5 is so employed, to connect the ends of the straps. It will be noted 30 that the heads of the nails are not exposed, no matter how the double or overlapping coupled straps are employed, whether they pass about the heads and the sides of the container, or whether they pass about the sides, top and bottom of the container, or whether 35 they pass in other directions, should the container be shaped other than rectangular. While Fig. 1 of the drawing shows the straps extending about the heads, the top and bottom, it is obvious that they may extend 40 about the heads and the sides.

The invention having been set forth, what is claimed as being useful is:

1. In a device for strapping and sealing containers, a pair of coupled alined overlying straps, the under strap being fastened 45 to the wall of the container, and means for connecting and sealing the adjacent ends of the outermost strap.

2. In a device for strapping and sealing containers, a pair of coupled alined overlying straps surrounding the container, means for securing one of the straps to the container, the outermost strap having its 50 ends overlapped, means for connecting said ends, and means for sealing and covering the ends, whereby the ends cannot be detached without detection.

3. In a device for sealing and strapping containers, a pair of overlying coupled 55 metallic straps, means for fastening one of the straps to the wall of the container, the outermost strap having overlapping ends, a connector for the reception of said ends, means passing through the connector and 60 through the overlapping ends and the under 65

strap and into the wall of the container, thereby connecting the parts in position, and means carried by and fastened to the connector, for sealing and covering the connected ends. 70

4. In a device for strapping and sealing containers, a pair of overlying coupled straps, means for connecting one of the straps to the container, the outermost strap having overlapping ends, a plate having an 75 opening extending longitudinally therethrough for the reception of said overlapped ends, said plate having a depression in its upper face, means passing through the plate and through the overlapped ends and 80 through the under strap and the wall of the container for securing said parts in position, and a seal of soft material engaging said depression, thereby covering and sealing 85 the adjacent overlapped ends.

5. In a device for strapping and sealing containers, a pair of overlying coupled straps, means for connecting one of the straps to the container, the outermost strap having overlapping ends, a plate having an 90 opening extending longitudinally therethrough for the reception of said overlapped ends, said plate having a depression in its upper face, means passing through the plate and through the overlapped ends and 95 through the under strap and the wall of the container for securing said parts in position, and a seal of soft material engaging said depression, thereby covering and sealing 100 the adjacent overlapped ends, and means for holding the seal in the depression.

6. In a device for strapping and sealing containers, a pair of overlying straps, means for securing one of the straps to the container, the under strap having struck up 105 loops for the reception of the outermost strap, the outermost strap having overlapping ends, and means for connecting and sealing said overlapping ends.

7. In a device for strapping and sealing 110 containers, a pair of overlying metallic straps, means for securing one of the straps to the wall of the container, the under strap having struck up loops arranged at intervals, through which the outermost strap longitudinally passes, said outermost strap having overlapping ends, a connector having a pocket for the said overlapping ends and provided with a seal receiving depression, means passing through the bottom of the 115 depression, and through the overlapped ends and through the under strap and into the wall of the container for holding the parts in place, and a seal in said depression, means for sealing and covering the overlapped 120 ends.

8. In a device for strapping and sealing containers, a pair of overlying metallic straps, means for securing one of the straps to the wall of the container, the under strap 125

having struck up loops arranged at intervals, through which the outermost strap longitudinally passes, said outermost strap having overlapping ends, a connector having 5 a pocket for the said overlapping ends and provided with a seal receiving depression, means passing through the bottom of the depression, and through the overlapped ends and through the under strap and into the 10 wall of the container for holding the parts

in place, and a seal in said depression, for sealing and covering the overlapped ends, the marginal wall of the depression being under-cut, to be engaged by the seal, for retaining the seal in the depression, whereby 15 it cannot be removed without detection.

In testimony whereof I hereunto affix my signature.

IRVING R. PIERSON.
